(57) **CLAIM**

The ornamental design for a sensor sleeve, as shown and described.

DESCRIPTION

FIG. 1 is a front, left perspective view of a sensor sleeve, in a flexed position, while attached to an outside portion of an undergarment;

FIG. 2 is a front, right perspective view of a sensor sleeve, in a relaxed position, showing our new design;

FIG. 3 is a front elevation view thereof;

FIG. 4 is a right side elevation view thereof, the left side elevation view being a mirror image thereof;

FIG. 5 is a rear elevation view thereof;

FIG. 6 is a top plan view thereof; and,

FIG. 7 is a bottom plan view thereof.

The broken lines of shorter length shown in the drawings illustrate portions of the sensor sleeve that form no part of the claimed design. The broken lines of longer length depict the environment and form no part of the claimed design. The appearance of any portion of article between the break lines forms no part of the claimed design.
